UNITED STATES PATENT OFFICE.

NELS G. ANDERSON, OF NAPA JUNCTION, CALIFORNIA.

TIE PLATE.

Application filed July 10, 1925. Serial No. 42,794.

This invention relates to an improved plate of the type known as tie plates and used upon railway ties to protect the tie and prevent it from being unduly worn by 5 pounding as a train moves along a track.

One object of the invention is to provide a tie plate which is so constructed that it may be firmly secured upon a tie by means of the spikes which serve to secure the rails.

10 Another object of the invention is to provide a tie plate including rigid abutment means for engaging one side of a rail base and a resilient clamp disposed for engagement with the other side of the rail base 15 and adapted to be moved into gripping engagement with the rail by means of a spike driven through an opening in the plate and into the tie.

Another object of the invention is to so 20 construct the tie plate and resilient rail gripper or clamp that this clamp, when moved into gripping engagement with the rail, may serve to hold the rail in position for engagement by the rigid rail-engaging 25 means and also serve to prevent the rail from creeping.

This invention is illustrated in the accompanying drawing, wherein—

Figure 1 is a top plan view showing a 30 portion of a rail secured upon a fragment of a tie by means of the improved tie plate; Fig. 2 is a sectional view taken on the line 2—2 of Fig. 1, and

Fig. 3 is a sectional view taken on the 35 line 3—3 of Fig. 1.

The tie 1 which is shown in Figs. 1 and 2 is of a conventional construction and will be formed of wood or any other suitable material into which spikes may be driven.

40 The tie plate 2 rests upon the upper face of the tie beneath the rail 3 and is provided at one side of the tie with a depending flange 4 which is of sufficient depth to engage the side face of the tie. A flange 4

45 has only been shown at one side of the plate but it will be understood that if desired a similar flange may be provided at its other side. In order to engage one side of the base 5 of the rail, there has been provided a shoulder 6 which extends across the plate for its full width and at its inner edge is provided with a flange 7 to overlap the rail base 5, as shown in Fig. 2. Referring to 50 this figure, it will be seen that at its inner side the abutment shoulder 6 is of a depth corresponding to the thickness of the rail

base at its side edge and that the base of the rail will fit snugly against the shoulder between the plate and the overhanging flange of the shoulder. Openings 8 are 60 formed through the shoulder and plate to receive the fastener spikes 9 and similar openings 10 are formed in the plate in proper spaced relation to the inner edge of the shoulder 6 so that the base of the rail 65 may fit snugly between the shoulder 6 and openings 10 and have its opposite side portion engaged by the heads of spikes 11 driven through the openings 10 into the tie. When the spikes 11 are in place, they 70 will serve to keep the rail in engagement with the shoulder 6 but the rail is liable to creep longitudinally. In order to prevent longitudinal creeping of the rail, there

has been provided a clamp 12 which is 75 formed of resilient metal. The base portion 13 of the clamp is welded into rigid engagement with the upper face of the plate adjacent one side edge thereof but the other end portion of the clamp is left free 80 from the plate and is reduced in thickness intermediate the length of the clamp to provide a head 14 which is joined to the base or end portion 13 by a neck 15. The head 14 has inner and outer side edge faces, the 85 inner side edge face being provided with teeth, as shown at 16 in Fig. 1, which are adapted to bite into the side edge of the rail base when the head of the clamp is forced 90 inwardly out of the normal position which is shown in Fig. 1. From an inspection of Fig. 1, it will be seen that the head normally extends in overlapping relation to an opening 17 which is formed in the plate and is adapted to receive a spike 18. A railroad spike of a conventional construction is 95 to be driven through this opening 17 into the tie and since a railroad spike is provided with a tapered lower end portion and above the tapered lower end portion is of a shape 100 to fit snugly in the opening, it will be readily seen that, when the spike 18 is driven into place, its tapered lower end portion will engage the outer side edge 19 of the head 14 and exert a cam action which will 105 force the head towards the rail and cause the teeth 16 to bite deeply into the base of the rail. When the spike 18 is fully driven into place, its head will overlap the head 14 of the clamp and the clamp will, therefore, 110 be prevented from being jarred upwardly out of engagement with the rail base by vi-

bration created when a train is moving along a track. When it is desired to release the rail, it is only necessary to remove the spikes 9, 11 and 18 and the rail will be freed so that the rail and also the plate may be removed from the tie.

Having thus described the invention, I claim:

1. A tie plate having a rigid member for engaging one side of a rail, and a member for engaging the other side of the rail, the last-mentioned rail-engaging member being formed of resilient material and having one end portion rigid upon the tie plate and its other end portion free and extending across an opening in the tie plate in partially overlapping relation to the opening whereby a fastener may be passed through the opening into a tie and force the resilient end portion of the clamp into gripping engagement with the rail.
2. A tie plate adapted to be secured upon a tie and having rigid means adapted for overlapping engagement with one side portion of a rail base, and a resilient clamp adapted to engage the other side of the rail base, said clamp being rigidly anchored to said plate and having a yieldable free end portion extending diagonally of the plate towards the rail-receiving portion thereof and extending across an opening formed in the plate whereby a fastener may be passed through the opening into a tie and force the yieldable free end portion of the clamp into position for gripping engagement with the rail base.
3. A tie plate adapted to be secured upon a tie and having rigid means adapted for overlapping engagement with one side portion of a rail base, and a resilient clamp adapted to engage the other side of the rail base, said clamp being rigidly anchored to said plate and having a yieldable free end portion terminating in a head having inner and outer side faces, said head normally extending

in overlapping relation to a spike-receiving opening in the plate and having its inner side edge face provided with rail-gripping teeth, and said head adapted to be forced into position for gripping engagement with a rail base by a spike driven through said opening and engaging the outer side edge face of the head.

4. A tie plate formed with openings to receive fasteners for securing the tie plate upon a tie and having rigid means adapted for overlapping engagement with one side portion of a rail base, and a resilient clamp adapted to engage the other side of the rail base, said clamp being rigidly anchored to said plate and having a yieldable free end portion normally extending across one of the fastener receiving openings of the tie plate in partially covering relation thereto and adapted to be forced inwardly into position for gripping engagement with the rail base by a fastener passed through the opening into a tie.

5. A tie plate adapted to rest upon a tie and having spike-receiving openings spaced a distance corresponding to the width of a rail base, a flange carried by said plate and adapted to overlap one side of a rail base, said openings adapted to receive spikes to secure the plate upon a tie and engage the base of a rail at opposite sides thereof, a clamp of resilient material rigid upon said plate and having a free end portion adapted to be forced into gripping engagement with a rail base at the opposite side thereof from said flange, said clamp having its free end portion normally extending across an opening formed in the plate whereby a spike may be driven through the last-mentioned opening into the tie and force the free end portion of the clamp into gripping engagement with the rail base.

In testimony whereof I affix my signature.

NELS G. ANDERSON. [L.S.]
